BOBBIN BUSHING

Paul C. Consoletti, Milford, Mass., assignor to Draper Corporation, Hopedale, Mass., a corporation of Maine

Application May 5, 1951, Serial No. 224,751

3 Claims. (Cl. 242—46.6)

This invention pertains to improvements in bobbins, and more specifically, to an improved bushing and the combination of that bushing with the bobbin itself.

It is a general object of the invention to improve bobbins such, for example, as those employed for receiving thread as the same is spun or twisted, and which are designed to cooperate with a rotatable spindle.

It is a more specific object of the invention to improve the performance of these bobbins as they are driven by their spindles and to provide an additional bushing which is adapted to prevent lateral movement of a bobbin with respect to the spindle, especially adjacent the upper end thereof, and to prevent the bobbin from working upwardly on the spindle and therefore losing its driving engagement.

It is a further object of the invention to devise bushings particularly adapted for the purpose herein described.

Bobbins made of wood or other materials are used in spinning and twisting and are usually frictionally driven by contact between a part of the bobbin and a cooperating spindle on which the bobbin is carried. Driving torque is transmitted from the rapidly rotated spindle to the bobbin through an acorn or clutch on the spindle which engages within a bushing in the lower end of the bobbin.

In actual practice the bore adjacent the tip of bobbins of the type herein described may or may not fit fairly closely the outside diameter of the spindle, and while that is true when the parts are relatively new, the actual difference in diameter of the parts becomes more pronounced after the bobbin has been used for some time. Especially with wooden bobbins, the predominating type, but also with others, the rough treatment to which they are subjected, that is, fluid treatment, steaming, repeated and violent shocks, and the continued wear incidental to doffing and donning and also to slippage of the bobbin on the spindle and to lateral vibrational movements thereof, the actual fit between the spindle tip and bobbin bore may become so loose as to permit the bobbin to vibrate laterally throughout a very considerable extent. This is accentuated by the fact that the packages built on these bobbins, as well as the bobbins themselves are not in exact balance and thus the vibrational forces which tend to be restrained by the spindle give rise to increased wear as well as the annoying vibrations.

It has been found that bobbins frequently fail to be driven properly, that is, they have a very definite and pronounced slip relative to the driving spindle so that they are actually not rotated at anywhere near the actual speed at which the spindle itself is driven. One reason for this appears to be a loosening of the engagement between the acorn or clutch elements and the bobbin and has been found to be, at least to an extent, caused by the fact that the upper end or tip end of the bobbin is not tightly engaged upon the spindle therefore permitting a lateral movement between the two and a vibration which actually causes the disengagement of the tapered surfaces, or other lifting of the bobbin with respect to the spindle mechanism which obviously gives rise to a change in driving conditions and to a lack of driving engagement

2

between the parts such as is necessary if the proper rotational speeds of the bobbins themselves are to be maintained. It is further to be understood that the taper between the acorn and the butt bushing may not be one devoted wholly toward maintaining ample frictional engagement for transmitting torque, since that would also increase the axial holding forces between the parts and prevent removal or doffing of the bobbin itself. Obviously the bobbins must be capable of being pulled from the spindles with a reasonable exercise of force and it is a fact that if that characteristic is to be realized, then the taper must be kept at an angle such that the actual driving force between the parts is not much greater than is necessary to maintain a more or less constant rate of rotation of the bobbin with and at the same speed as the spindle.

In overcoming the above mentioned difficulties, the invention has been directed toward elimination of the possibility of lateral movement of the bobbin with respect to the spindle, not only when the parts are relatively new, but also throughout the entire life of the bobbin. To this end a special bushing has been developed and is inserted to be fixedly held adjacent the upper or tip end of the bobbin and to engage the spindle with a resilient force so that although the parts offer no particular resistance to axial movement as when donning or doffing a bobbin, the lateral restraint necessary is resiliently, yet forcefully applied, so that no vibrational movement of the bobbin with respect to the spindle is experienced and so that even with the slight amount of wear which may occur over an extended period of time, there will be no tendency for the bobbin to become loose on the spindle, but rather it will be held thereon with virtually the same resilient gripping forces as prevailed when the parts were relatively new.

The invention will be described in the following part of this specification by more detailed description thereof with reference to the accompanying figures of drawing wherein:

40 Fig. 1 is a longitudinal section taken through a bobbin mounted upon a typical spindle and showing the manner in which the invention may be utilized.

Fig. 2 is a section showing to a greatly enlarged scale one form of bushing as applied to a bobbin.

45 Fig. 3 is a view similar to Fig. 2, but showing the same bushing when engaged upon a spindle.

Fig. 4 is a sectional view showing one of the early stages in the production of the bushing, subject matter of the invention.

50 Fig. 5 is an elevational view of the bushing showing a further step in its production.

Fig. 6 is a top view of the bushing at the stage shown in Fig. 5.

55 Fig. 7 is a top view of the bushing as the same appears when completed.

Fig. 8 is a sectional view through a modified form of bushing.

Fig. 9 is an end view of the bushing of Fig. 8.

60 Now referring to Fig. 1, a bobbin which may be made of wood, plastic, or any other satisfactory material, has a tapered barrel portion 10, a butt 11 and is bored axially with successively smaller diametered apertures progressing from the butt toward the tip. A bushing 12 in the butt may be formed in any one of the well known manners commonly employed and this bushing is flanged and held in the material at the butt of the bobbin by means adapted to prevent axial movement thereof once the same has been inserted.

70 The spindle itself comprises a blade 13, clutch type acorn 14 having a plurality of clutch segments 15, a whorl 16 and a continuing part 17 of the spindle adapted to extend into the bolster or other bearing means within

which the spindle blade, clutch and whorl are adapted to be rotated.

The bobbin herein illustrated is of the type adapted to be employed in looms, or what is known as a filling bobbin and therefore has a plurality of wire rings 18 for a purpose well known to those conversant with the textile art. It is to be understood that the invention, although illustrated with this type of bobbin and spindle may be applicable to others and need not be limited in any manner to the particular types of such means as have been illustrated herein. While a clutch has been shown for driving the bobbin as the spindle rotates, it is to be understood that a simple, tapered acorn may be used and in that event, the acorn merely engages frictionally within the bushing 12 and imparts rotational force thereto as well as exerting a certain amount of resistance toward removal of the bobbin from the spindle.

Under normal conditions, the bore indicated by numeral 19 at the tip end of the bobbin would be of such diameter as to accommodate the end 20 of the spindle without particular tendency for relative movement between the parts when they are new. However, according to the invention, a bushing 21 is inserted in the bore 19 which must obviously be of slightly greater diameter than if no bushing were to be used, and this bushing, better shown in Figs. 2 and 3, is so constructed as to prevent any relatively lateral movement between the bobbin and the spindle. The bushing 21 has a sleeve portion 22, a flange 23 and resilient or springlike, inwardly directed projections or fingers 24 which serve to grip the end of the spindle 13 more or less tightly, but in any instance, with sufficient force to prevent relative lateral movement. The bushing may be made of steel, brass or from any other suitable material having considerable resilience so that the fingers 24 have a pronounced and permanent spring in them, and preferably, from some material which may be worked so that the part is easily formed in presses or the like.

The bushing is of an outside diameter such as to be pressed into the bore 19 and to be held tightly therein and the flange 23 bears upwardly against a shoulder which marks the transition between the bore 19 and the larger bore continuing therefrom toward the bobbin butt. If desired, the interior tubular portion of the bushing may be indented as at 24' according to the usual practice with the driving bushing at the butt, for example, the bushing 12, Fig. 1. However, it has been found that if dimensions are such that the bushing 21 is pressed into the bobbin with a fair amount of force the relatively tight fit between the exterior of the bushing and the bore 19 serves satisfactorily to retain the parts in assembled position without any additional deforming such as just above described.

Now referring to Figs. 4-7, the successive steps in the formation of the bushing involve pressing and piercing or slitting operations which are very easily accomplished. In Fig. 4 the material has been shaped into a cup-like form thereby to form the sleeve 22 and the flange 23 while the opposite end is merely closed as in the formation of deep drawn parts of this type. At Fig. 5 the slitting or piercing operation has been performed and a series of cuts or slits 25 are made so as to divide the closing or transverse part of the bushing blank into a plurality of segments 26, herein shown as six in number, but any convenient number of subdivisions such as may prove most advantageous may be used. Then in Fig. 7 the next step is illustrated, that is, the segments 26 are pushed outwardly as by a plunger 27 of suitable diameter and since the part is of spring material, the segments do not remain in the outermost position to which they are flexed but tend to spring inwardly or back toward their original position once the inserted member is withdrawn. The resiliency of these generally triangular sectors or fingers as they may be called serves as illustrated in Fig. 3 to bear resiliently upon the outer periphery of the upper end of the spindle 13 and thus to hold the top portion of the bobbin in axial alignment with

the spindle and to prevent any tendency toward relative movement or vibration between the two.

While six segments or fingers have been found to serve satisfactorily, a greater number may be employed if the insertion of the deforming member has a tendency to strain and to crack the corners of the segments adjacent the outermost portion of the cut. The material from which the bushing is formed has sufficient resiliency to withstand the working or processing which it is subjected to in order to form the part as described.

In Figs. 8 and 9 a modified form of bushing has been shown and instead of working toward the formation of a cupped blank, tubular stock may be employed, a flange 23' formed by a suitable process on the tubular stock 15 which is of the proper diameter to form a sleeve 22' and then by a suitable metal working step, inwardly bent, resilient spring members 28 may be formed. These spring members 28 are preferably opposed at opposite sides of the sleeves and may be of a sufficient plurality suitably to grip the spindle as required. When bent inwardly as shown, the spindle should deform or flex the spring members 28 outwardly to a slight extent as the bobbin is placed on the spindle.

The position of the bushing 21 adjacent the tip of the 25 bobbin may be varied within limits, but should be as close to the tip of the bobbin as is practicable, its position, however, is generally limited by the length of the spindle blade or the extent to which that blade projects into the bobbin, it normally being a fact that the spindle blade extends toward the tip thereof, but stops at about the same distance from that tip as has been illustrated in Fig. 1.

The bushing 21 has no appreciable effect upon the force required to place the bobbin on the spindle or to withdraw it therefrom. In operation of the mechanism the resilient 35 fingers 24 or 28 or their equivalent, serve very well to restrain the bobbin against any lateral movement with respect to the spindle and therefore, unbalanced forces or other causes tending toward setting up vibration of the rotating mass have no effect upon the bobbin as has heretofore been experienced. Even after a very prolonged period of operation, the bobbin fits the spindle tightly and there is no tendency for lateral vibration to cause a loosening of the driving and holding engagement between the 40 butt bushing 12 and the part of the spindle against which it engages and the accompanying raising of the bobbin with respect to the spindle which results in a loss of driving engagement between the parts.

While one embodiment of the invention has been disclosed, it is to be understood that the inventive concept 50 may be carried out in a number of ways. The invention is, therefore, not to be limited to the precise details described, but is intended to embrace all variations and modifications thereof falling within the spirit of the invention and the scope of the claims.

I claim:

1. In a bobbin adapted to engage and be driven by a spindle and comprising a centrally bored barrel and butt, the latter of which is provided with a bushing for engaging an enlarged driving portion of the spindle and receiving 60 the driving impulse therefrom, that improvement which comprises a second bushing fixed within the bore of the bobbin adjacent the tip end thereof and comprising a sleeve, a positioning flange at one end and means on said sleeve for preventing withdrawal of the bushing from the bobbin, said sleeve having a plurality of independent, inwardly directed, resilient spindle gripping projections.

2. In a bobbin adapted to engage and be driven by a spindle and comprising a centrally bored barrel and butt, the latter of which is provided with a bushing for engaging an enlarged driving portion of the spindle and receiving 70 the driving impulse therefrom, that improvement which comprises a second bushing fixed within the bore of the bobbin adjacent the tip end thereof and comprising a sleeve, a positioning flange at one end of said sleeve and means on said sleeve for preventing the withdrawal of

the bushing from the bobbin and inwardly directed, independent, spring fingers at the other end for resiliently engaging the spindle.

3. In a bobbin adapted to engage and be driven by a spindle and comprising a centrally bored barrel and butt, the latter of which is provided with a bushing for engaging an enlarged driving portion of the spindle and receiving the driving impulse therefrom, that improvement which comprises a second bushing fixed within the bore of the bobbin and comprising a sleeve, a positioning flange at one end of said sleeve and means on said sleeve for preventing the withdrawal of the bushing from the bobbin and a plurality of inwardly bowed, independently flexed, spring members intermediate the ends of said sleeve for resiliently gripping the spindle. 15
